UNITED STATES PATENT OFFICE.

CHARLES E. NUTTING, OF HOPEDALE, MASSACHUSETTS, ASSIGNOR TO
DRAPER COMPANY, OF HOPEDALE, MASSACHUSETTS, A CORPOR-
ATION OF MAINE.

APPARATUS FOR HARDENING SPINNING-RINGS.

SPECIFICATION forming part of Letters Patent No. 792,917, dated June 20, 1905.

Application filed April 17, 1905. Serial No. 255,890.

To all whom it may concern:

Be it known that I, CHARLES E. NUTTING, a citizen of the United States, and a resident of Hopedale, county of Worcester, State of Massachusetts, have invented an Improvement in Apparatus for Hardening Spinning-Rings, of which the following description, in connection with the accompanying drawings, is a specification, like characters on the drawings 10 representing like parts.

This invention has for its object the production of apparatus for facilitating the hardening of spinning-rings and the like whereby the operation is simplified and made more rapid.

15 It has been found that the interior of a spinning-ring particularly requires hardening in order to resist the wear of the traveler when thrown outward and that the under surface of the outer flange and the adjacent surface 20 of the web of the ring should also be hardened.

Means have been devised for effecting the hardening operation by hand, the ring after 25 being heated to the proper hardening temperature being held on a mandrel which is then plunged into a bath of a cooling medium, and in United States Patent No 709,512, dated September 23, 1902, a machine is shown and described for automatically inserting an arbor

30 in a heated ring and then immersing the ring and arbor in a cooling-bath. The arbor in such apparatus fills the interior of the ring, and in practice it has been found that the internal surface of the ring is so protected by 35 the arbor that the cooling fluid is prevented from acting thereupon with the proper effect, so that the rings are imperfectly or insufficiently hardened at the portion most desirable.

In my present invention I have devised 40 means to hold the ring in position in such manner that its interior is left wholly unobstructed, so that the cooling liquid has free access thereto, and I also provide for preventing distortion of the ring by securely embracing the 45 periphery of its external flanged portion. At the same time the external surface of the ring

requiring hardening is left free to be acted upon by the cooling-bath.

My invention is particularly adapted for treating double-flanged reversible rings, a well-known and extensively-used form, the web of the ring having an inner and outer annular flange at top and bottom.

The various novel features of my invention will be fully described in the subjoined specification and particularly pointed out in the following claims.

Figure 1 is a side elevation of a ring-hardening apparatus embodying one form of my invention. Fig. 2 is an enlarged detail, partly 60 in section, on the line 2 2, Fig. 1, of the ring-support and the downhold for clamping the ring upon the support while the ring is subjected to the action of a cooling medium. Fig. 3 is a lower end view of the downhold; and 65 Fig. 4 is a sectional detail of the mechanism shown in Fig. 2, omitting the sustaining-arm, but taken on a plane at right angles to the line 2 2 of Fig. 1 and showing the downhold in clamping or operative position.

70 I have herein shown my invention as embodied in a machine such as is illustrated in the patent hereinbefore referred to, with such changes and rearrangement as are made necessary by the novel features of my invention.

75 Referring to Fig. 1, the frame 3, of suitable shape to sustain the operating parts, the inclined arm 6 thereof, which carries the support upon which the ring is clamped, the sliding carrier 7, longitudinally reciprocable in 80 said arm, and the actuating means therefor, consisting of the lever 15, 17 fulcrumed at 16 and provided with a roll 18 to coöperate with the cam 13, may be all substantially as in said patent, the lever-arm 17 extending through a 85 suitable aperture in the carrier 7.

The machine is operated by or through a pulley 4 on a shaft 5, having thereon a pinion 60 to engage the toothed periphery of the cam-plate 20, rotatable on a shaft 14, said plate hav- 90 ing a second cam 45 to operate the cooling-bath. This bath consists, preferably, of wa-

ter contained in a pan 34, carried by an arm 35, fulcrumed on the frame at 36 and connected by link 37 with a lever 38, (see dotted lines, Fig. 1,) fulcrumed at 39 and having a roll 44 to coöperate with the cam 45, whereby the pan will be raised to operative position at the proper time, all as in the patent referred to.

Referring to Fig. 2, the lower end of the arm 6 has bolted to it a base 61, provided at 10 its opposite side with grooves 62 to receive a flat plate 63, having upon it a cylindrical support 64, preferably of a diameter equal to that of the external flanges r r' of the ring, the lower flange, as r' , of the ring resting securely 15 upon the support. Upright guides 65, in-turned at their upper ends, are erected upon the plate 63 diametrically opposite each other to receive the lower ring-flange between them and to overlap the same, as shown in Fig. 2, 20 to position the ring on the support and prevent its lateral movement. A ring-stop to limit movement of the ring when slid onto the support will be described hereinafter. The lower end of the carrier 7 is herein shown as 25 made tubular at 66, Figs. 2 and 4, to receive an elongated sleeve 67, enlarged annularly at its lower end at 68 and interiorly beveled or coned, as at 69, the enlargement 68 having a sliding bearing on the part 70 of the arm 6. 30 A strong spring 71 is inserted in the tubular end of the carrier 7 and bears against the upper end of the sleeve 67, the latter being slideable longitudinally in the carrier and being held from rotation therein by a stud 72, Fig. 35 4, entering an elongated recess 73 in the sleeve. A downhold to engage and clamp the ring on the support is supported in the sleeve 67 and has a slight relative movement longitudinally, as will be explained, the downhold having a 40 bearing at its upper end in the sleeve at 74. I have herein shown the downhold as a tube 75, having an enlarged annular foot 76, externally coned at 77 to coöperate with the beveled face 69 of the lower end of the sleeve 67, 45 the foot being made radially compressible by longitudinal slots 78 in the downhold and extending from the lower edge of the foot upward the greater length of the tube 75. The interior of the foot is shaped to present an 50 annular seat 79, and below the seat the foot presents a depending circular wall 80, interrupted at intervals by the slots 78.

When the downhold is moved into operative position, the seat 79 engages the top of 55 the uppermost flange r of the ring, as shown in Fig. 4, and clamps the ring firmly upon the support 64, and the slight additional descending movement of the sleeve 67 causes the edge 69 to slide over the surface 77 of the downhold-foot 76, compressing the foot, so that the circular wall 80 firmly embraces and grasps the peripheries of the flanges r and r' of the ring. (See Fig. 4.)

In Fig. 2 the parts are in position for receiving a ring, and it will be supposed that a

ring has just been positioned on the support, a stud 81, fastened to the foot of the downhold, projecting downward in the path of the ring to stop it in proper position between the guides 65. The lower ends of the two opposite slots 78 of the downhold, which receive the guides 65, are preferably slightly beveled or flared at 78 $\times$, Fig. 3, to readily receive the in-turned upper ends of the said guides when the downhold descends. 75

In Fig. 1 a suitable furnace for heating the rings is shown at 82, and from the outlet or door 83 an inclined guide-chute 84 extends toward the arm 6, terminating a short distance therefrom. In the open end 61 of the arm a transverse strip 85 of metal is inserted at the level of the support 64 to partly bridge the space between the end of the chute 84 and the front of the ring-support. 80

The heated rings are directed from the furnace one by one to the chute, and the rings slide down the latter across the bridge-piece 85 onto the support 64, the ring to be treated being positioned thereon by the guides 65 and the ring-stop 81. The carrier-actuating mechanism is thrown into operation as in the patent referred to, and with the parts in the position shown in Fig. 2 the descending carrier acts through the spring 71 to move the sleeve 67 downward, carrying 90 with it the downhold, until the seat 79 engages the top of the upper flange r of the ring, while the circular wall 80 surrounds the peripheries of the flanges. When the downhold-seat engages the ring, the movement of the downhold is arrested; but as the carrier continues to descend the spring 71 is compressed, and it thereby forces the sleeve 67 down, so that the coned face 69 presses against the conical surface 77 of the compressible 95 foot 76 and causes the latter to close tightly upon the peripheries of the flanges. In Fig. 4 the parts are shown in such position, the ring being firmly clamped upon the support 64 with the foot 76 tightly gripping the peripheries of the flanges. The pan 34, containing water or other cooling liquid, is now raised by means of the cam 45 and intervening connections, as in the patent referred to, and the clamped ring is immersed in the cooling-bath, the liquid entering the downhold through the slots 78 and acting upon the unobstructed inner surface of the ring and also upon the outer surface of the web and the adjacent surfaces of the flanges. The proper 100 parts of the ring are thus hardened, and the pan 34 then returns to normal position, (shown in Fig. 1,) while the downhold and coöperating parts rise, releasing the ring, the sleeve 67 moving up to permit expansion of the 105 compressible foot and the downhold being lifted by means of a transverse pin 86, carried by the sleeve and extended through elongated slots 87 in the upper end of the downhold. 110

When the downhold rises, the in-turned 115 120 125 130

heads of the guides 65 hold the ring down and clear it from the downhold, the full operative position of the latter moving the ring-stop 81 into a hole 81^x in the plate. (See Fig. 4.) As the carrier rises the part 13^x of the cam 13 gives an additional rise to the carrier to lift the ring-stop above the ring and also to operate a knock-off device. The knock-off device is shown in Fig. 1 as 10 an arm 88, fulcrumed at 89 on the side of the arm 6 and having a depending finger 90 secured to its outer end, a spring 91, attached to its inner end, serving to normally maintain the arm 88 in inoperative position. A short 15 link 92 is pivoted at 93 on the carrier and has an elongated slot 94 entered by a pin 95 on the arm 88 between its fulcrum 89 and the point of attachment of the spring 91. When the carrier is given the additional upward 20 movement referred to from the position shown in Fig. 1, the link 92 quickly rocks the arm 88, causing the finger 90 to move downward and rearward against the ring on the support 64, hitting the ring a quick sharp blow, and 25 thereby knocking it off the support. The carrier then returns to the position shown in Fig. 1, and the apparatus is in readiness to act upon another ring.

The sleeve 67 and its enlarged end 68, provided with the conical or beveled face 69, constitutes means to compress the foot of the downhold upon the peripheries of the ring-flanges.

With the apparatus herein shown the rings 35 may be transferred directly from the usual bone chests to the heating-furnace 82 and fed therefrom to the mechanism for clamping and immersing, the proper hardening temperature being attained in the furnace.

Having fully described my invention, what 40 I claim as new, and desire to secure by Letters Patent, is—

1. In apparatus for hardening spinning-rings, in combination, a support for the ring, a hollow downhold to engage externally and clamp the ring on the support, means to effect relative movement of said downhold and support toward and from each other, and means to introduce automatically through the 45 downhold a cooling medium to act upon the interior of the clamped ring.

2. In apparatus for hardening spinning-rings, in combination, a support for the ring, an annular, apertured downhold to engage externally and clamp the ring on the support, means to move the downhold toward and from the latter, and means to introduce a cooling 55 medium through the apertured downhold and subject the interior of the ring to the action of such medium.

3. In apparatus for hardening spinning-rings, in combination, a support for the base of the ring, a slotted downhold movable toward and from said support and adapted to 60 engage the top of the ring and clamp it on the

support, and means to subject automatically the clamped ring to the action of a cooling medium, the latter passing through the slotted downhold to the unobstructed interior of the ring. 70

4. In apparatus for hardening spinning-rings, in combination, means to clamp the ring at its upper and lower ends, leaving the interior thereof unobstructed, and means to effect automatically immersion of the ring while 75 clamped in a cooling medium.

5. In apparatus for hardening spinning-rings, in combination, a support for the base of the ring, means to act externally on the ring and laterally position it upon the support, a reciprocating downhold to engage the ring externally and clamp it as positioned on the support, and means to subject automatically the unobstructed interior of the ring while 80 clamped to the action of a cooling liquid. 85

6. In apparatus for hardening double-flanged spinning-rings, in combination, a support for the bottom of the ring, a downhold to engage the top thereof and the periphery of its outer flange and clamp the ring on the support, 90 means to effect relative movement of the downhold and support toward and from each other, and means to subject the unobstructed interior and the exterior of the clamped ring below the held portion of its outer flange, to the 95 action of a cooling liquid.

7. In apparatus for hardening double-flanged spinning-rings, in combination, a support for the bottom of the ring, a reciprocating, radially-compressible downhold to engage the top 100 and the periphery of the adjacent outer flange of the ring, means to compress the downhold upon the periphery of the flange, and means to effect immersion of the ring in a cooling medium while so clamped and held. 105

8. In apparatus for hardening double-flanged spinning-rings, in combination, a support for the bottom of the ring, a tubular downhold having a radially-compressible, annular foot, means to move the downhold onto the top of 110 and clamp a ring on the support and to compress the foot upon the periphery of the adjacent ring-flange, and means to subject the ring interiorly and exteriorly to the action of a cooling liquid while the ring is clamped. 115

9. In apparatus for hardening reversible, double-flanged spinning-rings, in combination, a flat support for the bottom of the ring, a downhold having an annular seat to engage the top of the ring and a depending, annular and radially-compressible foot to embrace the peripheries of the top and bottom external flanges of the ring, means to operate the downhold to clamp the ring on the support and compress the annular foot upon the peripheries of its flanges, and means to effect automatically the immersion of the clamped ring in a cooling-bath. 120 125

10. In apparatus for hardening spinning-rings, means to externally engage and clamp 130

the ring, and means to automatically subject the interior of the ring while clamped to the action of a cooling liquid.

11. In apparatus for hardening spinning-rings, means to engage the top and bottom of the ring and the peripheries of the external flanges thereof, and means to automatically subject the free internal and external portions of the ring to the action of a cooling liquid.
12. In apparatus for hardening spinning-rings, a support adapted to sustain a ring, guides to position the latter on the support, a reciprocating, longitudinally-slotted tubular downhold having an annular seat to engage the top of the ring, and a depending foot on the downhold to embrace the outer periphery of the flanged portion of the ring, means to compress the foot about such portion, and mechanism to automatically effect immersion of the ring while so held in a cooling-bath.
13. In apparatus for hardening spinning-rings, a support adapted to sustain a ring, guides to position the latter on the support, a chute to direct the rings onto the support between the guides, a reciprocating, tubular downhold to engage the exterior only of the ring and maintain it on the support, and means to introduce a cooling liquid to the unobstructed interior of the ring through the downhold.
14. In apparatus for hardening spinning-

rings, means to externally engage and clamp the ring, means to effect automatically the immersion of the clamped ring in a cooling-bath, and a knock-off device to remove the ring after such immersion.

15. In apparatus for hardening spinning-rings, a ring-support, guides to laterally position a ring thereupon, a downhold to engage the top and external flanges of a ring and clamp it on the support, a ring-stop depending from the downhold to stop the ring in proper position with relation to the downhold, means to reciprocate the latter, and means to effect automatically immersion of the clamped ring in a cooling-bath.

16. In apparatus for hardening spinning-rings, a ring-support, means to position and prevent lifting of a ring on said support, a downhold movable toward and from the support, to clamp the ring on the latter, means to automatically immerse the clamped ring in a cooling-bath, and a knock-off device to discharge the ring from the support after immersion in the bath.

In testimony whereof I have signed my name to this specification in the presence of two subscribing witnesses.
